Baldwin & Wright

UNITED STATES PATENT OFFICE

ALFRED ARTHUR GODFREY, OF LONDON, ENGLAND; ASSIGNOR TO LINOLEUM MANUFACTURING COMPANY, LIMITED, OF LONDON, ENGLAND

MANUFACTURE OF LINOLEUM OR LIKE MATERIAL

Original application filed April 20, 1929, Serial No. 356,778, and in Great Britain May 2, 1928. Divided and this application filed May 22, 1930. Serial No. 454,693.

(This application is a division of my application No. 356,778, filed April 20th, 1929.)

This invention relates to the manufacture of linoleum or like material, and is a modification of the method described in my specification No. 356,778.

In the method described in my said specification, the edge of linoleum or like material is provided with a strip of material resembling a jointing material, by superimposing a strip of linoleum and a strip of thin hard separating material, winding the strips into a coil, pressing on to the edge thereof the material resembling the jointing material to cause the said material to be cut by the separating material and to be forced on to the edge of the linoleum, and then unwinding the coil and removing the separating material.

According to the present invention the method consists in assembling a plurality of pieces of the linoleum with pieces of separating material between them, the material resembling jointing material being pressed on to the edges of the separating material to cause the said material to be cut by the separating material and to be forced on to the edges of the linoleum pieces, and then removing the separating pieces.

The invention is illustrated in the accompanying drawings, in which Figure 1 is a perspective view, Figures 2 and 3 sections showing superposed linoleum pieces with the thin hard separating material between them,

Figure 2 showing the superposed pieces before the material resembling jointing material has been pressed thereon, and Figure 3 after the material has been pressed thereon, and Figure 4 a plan view showing a finished tessera. Figure 5 is a perspective view of a modification.

1 indicates pieces of linoleum which are superposed and separated by pieces 2 of thin steel which are slightly larger than the pieces

45 of linoleum. Sheets of material resembling mortar are then pressed against the edges of the pile and are cut through by the edges of the steel and adhere to the edges of the linoleum, as shown in Figure 3. The pieces 50 are then separated, and the tesserae thus

formed will be provided, on each edge, with a thin strip of material 3 resembling mortar, as is shown in Figure 4.

The tesserae thus formed may, if desired, be laid upon the usual canvas backing to form any desired pattern, and rolled, or the tesserae 55 may be employed as separate blocks.

In the modification shown in Figure 5, plain cut tesserae 4 are placed edge to edge on a steel strip 5, which is slightly wider than the linoleum pieces and which is then wound into a coil.

The sheet of material resembling mortar is pressed on to the faces of the coil, the sheets thus being cut through by the edges of the 60 steel strip, and adhering to the edges of the linoleum pieces. The coil is then unwound, and the pieces of linoleum removed and replaced with their other edges parallel with the edges of the steel strip, as is shown in 65 this figure, the process then being repeated.

What I claim is:—

1. The method of providing the edge of linoleum with a strip of material resembling a jointing material, which consists in assembling a plurality of pieces of linoleum with thin, hard separating material between the pieces, pressing on to the edges thereof the material resembling jointing material to cause said material to be cut by the separating material and to be forced on to the edge of the linoleum, and removing the separating material.

2. The method of providing the edge of linoleum with a strip of material resembling a jointing material, which consists in assembling a plurality of pieces of the linoleum with thin metal between said pieces, pressing on to the edges thereof the material resembling jointing material to cause said material to be cut by the thin metal and to be forced on to the edge of the linoleum, and removing said thin metal.

3. The method of providing the edge of linoleum with a strip of material resembling a jointing material, which consists in assembling a plurality of pieces of the linoleum with thin hard separating material between said pieces, the edges of the separating material extending slightly beyond the edges of 100

the linoleum, pressing on to the edges thereof the material resembling jointing material to cause said material to be cut by the projecting edges of the separating material, and to be forced on to the edge of the linoleum, and removing said separating material.

4. The method of providing the edge of linoleum with a strip of material resembling a jointing material, which consists in assembling a plurality of pieces of the linoleum with thin metal between said pieces, the edges of said thin metal extending slightly beyond the edges of the linoleum, pressing on to the edges thereof the material resembling jointing material to cause said material to be cut by the projecting edges of the thin metal, and to be forced on to the edge of the linoleum, and removing said thin metal.

5. The method of providing the edge of linoleum with a strip of material resembling a jointing material, which consists in superimposing a plurality of pieces of said linoleum with pieces of thin hard separating material between them, pressing on to the edges thereof the material resembling jointing material to cause said material to be cut by the separating material and to be forced on to the edges of the linoleum pieces, and removing said separating material.

30 6. The method of providing the edge of linoleum with a strip of material resembling a jointing material, which consists in superimposing a plurality of pieces of said linoleum with pieces of thin metal between them, pressing on to the edges thereof the material resembling jointing material to cause said material to be cut by the thin metal and to be forced on to the edges of the linoleum pieces, and removing said thin metal.

40 7. The method of providing the edge of linoleum with a strip of material resembling a jointing material, which consists in superimposing a plurality of pieces of said linoleum with pieces of thin hard separating material between them, the edges of the separating material extending slightly beyond the edges of the linoleum, pressing on to the edges thereof the material resembling jointing material to cause said material to be cut by the projecting edges of the separating material and to be forced on to the edges of the linoleum pieces, and removing said separating material.

55 8. The method of providing the edge of linoleum with a strip of material resembling a jointing material, which consists in superimposing a plurality of pieces of said linoleum with pieces of thin metal between them, the edges of said thin metal extending slightly beyond the edges of the linoleum, pressing on to the edges thereof the material resembling jointing material to cause said material to be cut by the projecting edges of the thin metal and to be forced on to the edges of the

linoleum pieces, and removing said thin metal.

In testimony that I claim the foregoing as my invention I have signed my name this ninth day of May, 1930.

ALFRED ARTHUR GODFREY.
